UNITED STATES PATENT OFFICE.

CHARLES C. SOUTHWELL, OF MILWAUKEE, WISCONSIN.

DENTAL BREATH-GUARD.

SPECIFICATION forming part of Letters Patent No. 319,338, dated June 2, 1885.

Application filed September 17, 1884. (No model.)

To all whom it may concern:

Be it known that I, CHARLES C. SOUTHWELL, of Milwaukee, in the county of Milwaukee, and in the State of Wisconsin, have 5 invented certain new and useful Improvements in Breath-Guards for Dentists' Use; and I do hereby declare that the following is a full, clear, and exact description thereof.

My invention relates to breath-guards for 10 dentists' use; and it consists in peculiarities of construction, as will be fully described hereinafter.

In the drawings, Figure 1 is a perspective view showing my device in position for use. 15 Fig. 2 is a perspective view of the device detached from the face. Fig. 3 is a like view of the supporting-plate, and Fig. 4 shows in perspective also one form of the breath-guard.

A is the supporting-plate of my device, which 20 is bent rearward and has its upper edge concaved, so as to conform to the parts of the face on which it is to be applied—that is, the upper lip and the base of the nostrils. The ends are bent in and under to form the hooks a a, 25 wherein the upper edge of the rubber dam B is passed, the plate A being thus held in position, as desired.

In the center of the supporting-plate A, and 30 made integral with the same by punching, or fastened in any suitable manner on its outer face, is the staple a', wherein is received the lug c, that is hinged or otherwise attached to the inner edge of the breath-guard C. This latter may be made of various forms, according to the location of the tooth being operated upon, and consequently according to the position the operator has to take in relation to it, and also to the direction of the exhaled breath of the sitter. The guard is for that

reason interchangeable, its connection with 40 the supporting-plate adapting it to be readily removed and replaced to suit the circumstances of the case.

As it is sometimes advisable to use the guard without the rubber dam, in which case 45 the hooks a a would be of no use in supporting the plate A, I provide close to each end of the said plate, and on its outer face, a fastening device of any suitable form, as shown at a² a², by means of which and of the band D 50 the device may be held in the position desired.

Having thus described my invention, what I claim as new, and desire to secure by Letters Patent, is—

1. In a dental breath-guard, the combination of a support adapted to fit the upper lip with a guard hinged thereto, so as to be capable of adjustment, as described. 55

2. The combination of the plate A, having 60 staple a' and fastenings a² a², the breath-guard C, having the lug c, and the band D, substantially as shown and described, and for the purpose set forth.

3. In combination with the rubber dam B 65 and fastenings, the supporting-plate A, having hooks a a, staple a', and fastenings a² a², the breath-guard C, having the lug c, and the band D, substantially as shown and described, and for the purpose set forth. 70

In testimony that I claim the foregoing I have hereunto set my hand, at Milwaukee, in the county of Milwaukee and State of Wisconsin, in the presence of two witnesses.

CHAS. C. SOUTHWELL.
